RETORT FOR TREATING CARBONACEOUS MATTER

Filed June 9, 1928

INVENTOR
PAUL DVORKOVITZ
BY HIS ATTORNEYS

Horson and Horson

UNITED STATES PATENT OFFICE.

PAUL DVORKOVITZ, OF KENSINGTON, ENGLAND.

RETORT FOR TREATING CARBONACEOUS MATTER.

Application filed June 9, 1928, Serial No. 284,204, and in Great Britain March 8, 1927.

This invention relates to apparatus for use in the process of treating coal, and other carbonaceous matter, whereby oils of the paraffin series are obtained therefrom, the coal, or other carbonaceous matter, according to this process being contained in closed vertical or inclined, externally heated retorts to the upper ends of which preheated gases are admitted from a preheater which is separate 5 from the retort chamber, the said gases being for instance, hydrogen water gas, producer gas, or ordinary coal gas, the temperature of the said gases being controlled so that the heat produced in the retorts is such 10 as will liberate from the charge in the said retorts only, or mainly, the desired light oils of the paraffin series, the heat required for this purpose being not higher than about 500 degrees centigrade and not lower than about 15 280 degrees centigrade.

In apparatus of the aforesaid kind the light oils produced will pass downwards in the retorts and then pass out by an outlet at, or towards, the bottom thereof, leaving a residue in the said retorts consisting of, or comprising, denser constituents and carbon, and this invention has for its object to provide an improved apparatus wherein the said residue is subjected to treatment by preheated neutral gas and, if desired, superheated steam may be used in conjunction with the neutral gas, whereby heavy oils (that is oils heavier than the before-mentioned light oils) are obtained therefrom in an efficient and 30 economical manner.

According to this invention the apparatus comprises a retort of the kind hereinbefore referred to which is mounted upon a similar retort, valvular means being provided, whereby the said retorts can, when desired, be put into communication, so that the residue in the upper retort can pass into the lower retort for further treatment. There is thus provided a plurality of vertical retorts superposed one above the other. Valves controlling communication between the retorts are likewise provided.

Means are also provided whereby each of the retorts is externally heated and whereby preheated carrier gas is admitted thereto, and this may be effected for instance in the same manner as described in Patent No. 1,627,321 granted to me on May 3, 1927, in which there is disclosed an apparatus wherein gas for introduction into the retorts is preheated 50 in a heater which is separate from the retort

chamber. Of course other known or convenient means may be employed.

From the above it will be seen that there are provided separate retort chambers in 60 which each of retorts is set.

When a charge of carbonaceous material contained in the upper retort has become subjected to treatment and the required light oils obtained therefrom, the valve or valves 65 controlling communication between the retorts is, or are, operated so that the residue in the said upper retort passes into the retort beneath it where it is subjected to a higher temperature in accordance with the products 70 to be obtained therefrom, such, for instance, as the heavier oils of the paraffin series.

The upper retort, and also if desired the lower retort may be provided with means whereby the contents, during treatment, or at 75 intervals during treatment, can be subjected to mechanical agitation, or loosening-up, in such manner that the said contents are very efficiently subjected to the heat applied to the retort, or retorts, and the process thereby expedited and generally rendered more complete and efficient.

The vapours pass from the retorts to a series of condensers (not shown) from which the products of condensation can be removed 80 separately, as desired in well known manner.

The accompanying drawing shows in sectional elevation an apparatus provided with upper and lower chambers within each of which is a retort, the upper retort being superimposed on the lower retort in accordance with this invention. In the drawing one 90 of the retorts is shewn partly in section and provided, by way of example, with mechanical means for agitating, or stirring, or loosening-up, the coal or other carbonaceous matter, under treatment, contained in the said retort.

Referring to the drawing A and A¹ are two retort chambers arranged side-by-side 100 and having vertical retorts B and B¹ set therein which are superimposed on vertical retorts C and C¹ set in retort chambers D and D¹ beneath the retort chambers A and A¹ respectively. Each of the retort chambers is heated by the hot products of combustion derived from the furnace E situated at one side of the retort chamber D¹, the said hot products passing from the upper part of the said furnace through passages e formed 105 in the walls of the furnace and the retort chambers and enter the respective chambers 110

through ducts c^1 each of which may be provided with dampers (not shewn) operable from the exterior of the walls whereby the external heating of the respective retorts is controlled. Each retort B and B^1 is provided at top with a charging hopper F arranged at one side thereof and at the bottom with a valve c which controls communication between it and the lower retorts C and C^1 respectively, which is provided at bottom with discharging means d . Each of the hoppers F is provided with duplex valves f and f^1 which will permit of charging without putting the insides of the retorts B and B^1 into communication with the outer air.

Within each of the retorts B and B^1 is a rotatable screw, or conveyor, G onto the upper part of which the coal, or other carbonaceous matter, to be treated is fed from the charging hopper F. This screw, or conveyor G, besides feeding the charge of coal, or other carbonaceous matter, downwards, acts to feed the said charge towards the wall of the retorts B and B^1 whereby the heat of the said wall is more efficiently utilized, and the said screw also agitates, stirs, or loosens up the charge under treatment to allow the better penetration of the heat in the retort chambers A and A^1 derived from the products of combustion in the furnace E and from the heating agent (such for example as hydrogen, or water-gas, or producer-gas, or ordinary coal-gas) admitted at the top of the said retort.

The screws, or conveyors, G may be mounted within the retorts in any convenient manner and be provided with any suitable means for rotating them. This is shewn as being effected as follows:—The lower end of the shaft of each screw, or conveyor G, is rotatably mounted on the spider g secured to the interior of the retort and the upper end of the said shaft is rotatably mounted in bearings on the top cover b of the retort and has secured thereto a worm wheel b^1 for engagement by a worm secured to a driving shaft (not shewn) to which rotary motion may be transmitted from any suitable source.

The upper part of the retorts B and B^1 projects above the roof of the retort chambers and this projecting part is enclosed by brick-work which constitutes a support for the said retorts.

The heating agent (which I refer to as the gases) to be admitted at the top of each of the retorts is led, from any suitable source of supply, through a pipe H to a preheater H^1 consisting of a number of coils, convolutions, or the equivalent, of tubing situated in a chamber I in communication with the furnace E. The gases enter the preheater H^1 at the lower part thereof and, after circulating through the said preheater are led by a pipe h at the top of the said preheater through suitably arranged branch pipes h^1 controlled

by valves (not shewn) to the top of the interior of each of the said retorts.

The gases admitted into the retorts B and B^1 in conjunction with the external heating of the said retorts by the products of combustion from the furnace E produce the required temperature necessary to liberate from the charge the vapours of the required light oils which will pass downwards and, owing to the said retorts being heated by gases which are hottest at the upper ends of the said retorts and owing also to the currents of gases and vapours inside the retorts being constantly flowing in a downward direction, which is facilitated by the stirring, or loosening-up of the charge by the mechanical agitator G, the said vapours of the light oils will, as soon as they are formed, pass rapidly downwards without danger of becoming decomposed and will pass out from the retorts by outlet pipes J from which they eventually pass into air condensers.

When a charge of carbonaceous material contained in the upper retorts B and B^1 has been subjected to treatment and the required light oils obtained therefrom, the valves c controlling communication between the said retorts and the lower retorts C and C^1 are opened so that the residue in the said upper retorts passes into the said lower retorts where, after the valve c has again been closed, it is subjected to a temperature in accordance with the products to be obtained therefrom, such for instance, as the heavier oils of the paraffin series.

If desired the lower retorts C and C^1 may be provided with means whereby the contents, during treatment, or at intervals during treatment, can be subjected to mechanical agitation, stirring, or loosening-up, and this may be effected by providing each of the said retorts with a screw, or conveyor, such as G shewn in the upper retort B.

The gases admitted into the lower retorts C and C^1 in conjunction with the external heating of the said retorts produce the required higher temperature necessary to liberate from the charge delivered thereinto from the upper retorts B and B^1 the required products to be obtained therefrom such for instance as the vapours of the heavier oils of the paraffin series which will pass downwards and out from the said retorts by outlet pipes K from which they eventually pass to air condensers in a similar manner to that described with regard to the vapours of the light oils of the paraffin series.

I claim:—

1. Apparatus of the type described comprising two superposed vertical retorting chambers, the upper chamber at the bottom thereof communicating directly with the lower chamber at the top thereof so as to allow discharge of solid material from the upper chamber into the lower chamber, a valve for

controlling the communication between said chambers, means for introducing a gas into the upper chamber at the top thereof, an inlet for solid material in the upper part of the upper chamber and an outlet for solid material at the lower part of the lower chamber, means for heating said chambers, mechanical agitating means disposed in the upper chamber and a gas outlet for each of the said chambers at the lower part thereof.

2. Apparatus of the type described comprising two superposed vertical retorting chambers, the upper chamber at the bottom thereof communicating directly with the lower chamber at the top thereof so as to al-

low discharge of solid material from the upper chamber into the lower chamber, a valve for controlling the communication between said chambers, means for introducing a gas into each of said chambers at the top thereof, an inlet for solid material in the upper part of the upper chamber and an outlet for solid material at the lower part of the lower chamber, means for externally heating said chambers, mechanical agitating means disposed in the upper chamber and a gas outlet for each of the said chambers at the lower part thereof.

In testimony whereof I have signed my name to this specification.

PAUL DVORKOVITZ.
